EXTRUDED MEMBER FOR EQUIPMENT DRAWERS OR THE LIKE

Stanley E. Beale, Bradbury, Calif., assignor to Applied Development Corporation, Monterey Park, Calif., a corporation of California

Original design application July 30, 1962, Ser. No. 71,109.
Divided and this application Jan. 31, 1964, Ser. No.
78,439

Term of patent 14 years

(Cl. D13—6)

FIG. 1 is an end view of the extruded member for equipment drawers or the like showing the new design; FIG. 2 is a side elevation, taken from the right in FIG. 1, of a portion of the extruded member; and

FIG. 3 is an elevation view, taken from the left in FIG. 1, of a portion of the extruded member showing the new design.

The extruded member is broken away at the center in FIGS. 2 and 3 to indicate indeterminate length.

This application is a division of my copending application for design patent, Serial No. D. 71,109, filed July 30, 1962, for Equipment Drawer, now abandoned.

I claim:

The ornamental design for an extruded member for equipment drawers or the like, as shown and described.
